UNITED STATES PATENT OFFICE.

WINSTON F. STOODY, SHELLEY M. STOODY, AND CHARLES H. STOODY, OF WHITTIER,
CALIFORNIA.

FISHTAIL BIT.

Application filed August 31, 1923. Serial No. 660,363.

To all whom it may concern:

Be it known that we, WINSTON F. STOODY, SHELLEY M. STOODY, and CHARLES H. STOODY, citizens of the United States, residing at Whittier, in the county of Los Angeles and State of California, have invented new and useful Improvements in Fishtail Bits, of which the following is a specification.

10 This invention relates to fishtail bits.

An object of the present invention is to provide a fishtail bit having the usual substantially flat body and being provided on the corners of its cutting end with forwardly projecting and longitudinally extending thickening ridges or wings which are formed on the forward side of the corners as to direction of rotation of the bit.

An important object is to provide a fishtail bit having the longitudinal edges of its cutting corners so thickened from front to back or built up, as it were, as to provide a very materially increased longitudinal edge which is ordinarily subjected to a reaming action and therefore causes the flat body to wear away to a heel-like or rounded corner. An advantage of the present invention is that by relatively thickening the longitudinal edges of the corners of the bit, the life of the corners is very greatly increased, and from actual practice and use of the invention in drilling deep wells it is found that instead of the corners rounding off or heeling, the lower ends of the bit cut substantially on a straight, transverse line from the original end face back to the terminus of the built up or widened edges.

Other objects and advantages will be made manifest in the following specification of embodiments of the invention illustrated in the accompanying drawings, wherein:

Figure 1 is a side elevation of the improved bit.

Fig. 2 is an edge view of the bit.

Fig. 3 is a cross section on line 3—3 of Figure 1.

Fig. 4 is a side elevation of another form of the bit.

Fig. 5 is a cross section on line 5—5 of Figure 4.

Fig. 6 is an edge view of a form of the edge with the wing.

Fig. 7 shows diagrammatically the building up, by welding, of an edge wing.

The bit of the present invention consists of the usual flat body 2 having a head 3 with a threaded pin 4. The lower end of the blade 2 may be continuous or somewhat bifurcated, as at 5, and the lower, transverse end of the blade is provided with inwardly convergent cutting edges 6—6.

An important feature of the present tool consists of forwardly projecting ridges 8 extending along the longitudinal edges of the cutting corners of the blade. These wings are formed on the forward side only of the bit corners and are provided either with concentric reaming faces 9 or the outer faces may be backed off as at 10 to provide for rake or back clearance behind the front edges of the wings, as in Figure 4.

Most forms of fishtail bits have the lower corners bent or struck forwardly as indicated by the dotted line 12 in Figures 2 and 6, and in Figure 2 the edge widening wing 8 is shown as projecting at 8a beyond the lip or end edge 6 of the blade, while in Figure 6 the widening wing edge terminates at its lower end at the edge 6. Figures 2 and 6, therefore, show simply different forms of widening wings.

The direct advantage of the edge widening wings 8 is that the reaming edges 9 of the tool are very materially widened and therefore have a greater length of life as well also as increasing the reaming action of the longitudinal edges of the tool. It has been found from actual use of the winged tool that the cutting edges 6 as they wear do not round off at the corners of the blade but continuously wear back on a line which is substantially perpendicular to the axis of the bit, and therefore the bit presents a straight, transverse, cutting bottom edge back to the upper ends of the wings 8 and all heeling or rounding tendency of the corners is wholly overcome.

By our method, fishtail tools may be formed in the original process of manufacture by forging the wings 8 integrally with the blade, or in other cases finished bits of ordinary type may be provided with built up wings 8, as in Figure 7, by fusing and welding onto the front of the corners of the blade a high-grade steel stock as from a pencil 13 of steel which becomes thoroughly bonded with the blade 2 and can be built up to any desired length and width and cross

section, a preferred form of which is shown in Figure 7. A welding torch T is indicated in Figure 7 as showing how the pencil stock may be fused and welded onto the blade 2.

5 The present invention, therefore, consists broadly in forming on or building up upon the cutting corners or edges of bits cutting portions which may be built on worn bits or bits of standard construction by fusing 10 or welding.

By providing the lower portions of the 15 longitudinal edges of the fish tail bit with widened cutting wings, the wear thereon is minimized, and the fish tail bit will retain the same width indefinitely, making it unnecessary to follow up the drilling operation with a reamer to enlarge the hole drilled. Such reaming operation is necessary with 20 the use of the ordinary fish tail bit, which in its use becomes quickly worn and pre-

sents a smaller width, making the use of the reamer necessary.

Further embodiments, modifications and variations may be resorted to within the principle of the invention.

25 What is claimed is:

A fish tail drill bit having a downwardly cutting edge and provided with parallel longitudinal edges having the cutting corners of the lower portions of said edges 30 provided with forwardly widened cutting wings, the outer faces of said wings merging with the longitudinal edges of the bit and being concentric to the longitudinal axis of the bit.

35 In testimony whereof we have signed our names to this specification.

WINSTON F. STOODY.
SHELLEY M. STOODY.
CHARLES H. STOODY.
